A. E. FOWLE

METHOD OF AND APPARATUS FOR DRAWING SHEET GLASS

Filed Oct. 3, 1921

UNITED STATES PATENT OFFICE.

ARTHUR E. FOWLE, OF TOLEDO, OHIO, ASSIGNOR TO THE LIBBEY-OWENS SHEET GLASS COMPANY, OF TOLEDO, OHIO, A CORPORATION OF OHIO.

METHOD OF AND APPARATUS FOR DRAWING SHEET GLASS.

Application filed October 3, 1921. Serial No. 504,970.

To all whom it may concern:

Be it known that I, ARTHUR E. FOWLE, a citizen of the United States, residing at Toledo, in the county of Lucas and State of Ohio, have invented new and useful Improvements in Methods of and Apparatus for Drawing Sheet Glass, of which the following is a specification.

This invention relates to improvements in the art of drawing sheet glass, and especially to an improved system and apparatus for drawing a plurality of sheets of glass simultaneously from a bath of molten glass, passing the same in separable contact with one another about a bending device and through a drawing mechanism, and then separating the several sheets so that they may be individually annealed and cut into the desired sizes.

In the application of Joseph P. Crowley, Serial Number 386,440, filed June 4, 1920, is disclosed a system of drawing sheet glass wherein a pair of sheets are drawn vertically from a bath of molten glass, and after becoming partially set so that they will not adhere to one another, are brought into contact and bent collectively about a single bending roller and then passed through a single drawing mechanism and into a leer. Such a system doubles the output of the sheet drawing apparatus, and also has the advantage that a traveling surface of glass (the lower sheet), is interposed between the upper sheet of the pair and the operating portions of the drawing and bending devices so that nothing encounters this upper sheet to mar its surface.

The present invention is an addition to, and improvement on the glass sheet drawing system set forth in this Crowley application. In the present system the sheets are drawn, as before, in separable contact with one another but as they enter the leer, mechanism is provided whereby the sheets are separated and conveyed individually through the leer from which they emerge onto individual cutting tables. In this way both surfaces of each sheet are exposed throughout the travel of the sheet through the leer, thus securing more uniform and satisfactory annealing. Also since each sheet emerges separately onto its own cutting table the process of severing the respective sheets into suitable lights or sections is greatly facilitated.

In the accompanying drawings which show two approved forms of apparatus for carrying out this invention:

Fig. 1 is a longitudinal vertical section through the glass drawing apparatus and the leer.

Fig. 2 is a longitudinal vertical section on an enlarged scale of the leer and a portion of the drawing mechanism, showing a slightly different form of the invention from that shown in Fig. 1.

Fig. 3 is a fragmental perspective sectional view taken substantially on line 3—3 of Figs. 1 and 2, indicating one of the devices for slidably supporting the edges of the upper sheet.

At 1 is indicated a portion of a draw-pot or receptacle containing a supply of molten glass 2. This pot is preferably in direct communication with a continuous tank furnace, wherefrom a substantially constant level of molten glass is continuously supplied to the pot 1. A sheet of glass 3 is drawn upwardly from the bath 2 between suitable edge holding devices 4 and then bent over cooled bending roller 5 and passed horizontally over suitable intermediate guide rolls 6 and 7 through a sheet-drawing mechanism indicated generally at 8. This sheet-drawing mechanism may be of any approved form but as here shown comprises an endless traveling flattening table 9 and an upper endless traveling draw mechanism 10 which preferably bears only upon the edge portions of the sheet of glass. Drawing mechanisms of this character are disclosed, for example, in the patent to Colburn, 1,248,809, granted Dec. 4, 1917. A second sheet of glass 11 is also drawn upwardly from the molten glass 2, parallel with the sheet 3, and after becoming partially set is deflected about a cooled bending roller 12 and passed about the bending roll 5 beneath the sheet 3. This sheet 11 also passes over the guide rolls 6 and 7 and through the draw mechanism 8 beneath the sheet 3 and in direct contact with these devices. The sheets 3 and 11 although still somewhat plastic and workable, are set by the time they reach the bending roll 5, to such a degree that they will not adhere to one another. It will be noted that the sheet 3 throughout its travel over the bending roll 5 and through the draw mechanism by which time it has become flattened and set in substantially its final form, rests upon a travel-

ing surface of glass, that is the lower sheet 11, and does not come in direct contact with any portions of the drawing or bending mechanism. Since the contacting glass surfaces will not scratch or mar one another the upper sheet 3 will pass through the entire drawing operation without having its fine fire-polished surface injured in any way, and the lower sheet 11 will be subject to no more 5 damaging influences than are incidental to the processes now in use wherein only a single sheet is drawn. All of the above is substantially as set forth in the Crowley application noted above.

10 The present invention aims to improve and simplify the annealing and cutting operations as applied to sheets drawn by the process just described. Beyond the sheet drawing mechanism and in direct communication therewith is a leer 13 which is of considerable length and has its temperature regulated from a rather high heat in the end where the sheets enter from the drawing mechanism to a much cooler temperature 15 at the end 14 where the sheets emerge. At 15 is indicated a fire box containing suitable burners 16 for supplying a mild heat to the entry end of the leer, the temperature at this point being substantially that of 20 the sheets as they emerge from the draw mechanism. Other burners or sources of heat may be disposed at intervals throughout the length of the leer so as to provide for a gradual reduction in the temperature 25 from one end to the other. As shown in Fig. 1, the leer is broken away at 17 to indicate that a considerable portion of its length has been omitted in the drawings. When the sheets 3 and 11 emerge from the drawing 30 mechanism 8 and enter the leer they are flat and set in their final sheet form, and although still quite hot are no longer plastic. However these sheets, as is the case with finished sheets of glass of any considerable length, have a certain amount of elasticity and it is possible to spring the sheets apart without breaking them or destroying their flatness. As shown in Fig. 35 1 of the drawings a conveyer is provided for the lower sheet 11 comprising a series of spaced supporting rolls 18. These rolls at the hotter end of the leer may be covered with asbestos or suitable refractory material and as the temperature decreases the rolls 40 may be made of any suitable material that will not scratch the surface of the glass. All of these rollers are preferably driven at such a speed that their peripheral travel will conform to the speed at which the sheet 45 is drawn by the mechanism 8. It will be noted that the first few rollers 19 at the entry end of the leer are arranged along a gentle slope, the angle being about that through which the sheet 11 will bend under its own weight without danger of break- 50 age. After the sheet 11 has been deflected downwardly a few inches from the horizontal plane in which it entered the leer, the rollers 18 are again mounted with their axes in the same horizontal plane so that 55 the sheet 11 will continue throughout the remainder of the leer in a horizontal plane parallel to that of the upper surface of the rollers. A second set of conveying rollers 20 is located a few inches above and 60 parallel with the conveying rollers 18. These rollers 20 are similar in all respects to the rollers 18 and also preferably driven. Near the entry end of the leer a series of somewhat smaller rollers 21 are located between the sheets 3 and 11 and the upper sheet 3 is gently deflected upwardly over these rollers 21 onto the series of upper supporting rolls 20. A pair of rollers 22, between which the two sheets pass loosely, are located just 65 beyond the drawing mechanism 8. These rollers 22 prevent the separation of the sheets carrying back too far into the drawing mechanism.

70 Between the line of separation of the two sheets and the first upper supporting roller 21, stationary supports such as 30, projecting under the edge portions of the upper sheet 3, may be used. These stationary supports may be made of metal or refractory 75 material, and may be made rather thin so as to support the upper sheet where the space between the separating sheets is hardly sufficient to allow the introduction of a supporting roller. These supports 30 80 preferably extend under only the edge portions of the sheet 3, and since these edge portions are usually more or less marred and deformed by the edge forming rollers 4, and must be eventually discarded, any 85 scratching resulting from the sliding contact of the sheet with the supports 30 is immaterial. Although it is preferable to use these supports 30, they are not absolutely necessary, since the distance between 90 the supporting rollers 21 and 22 is not great and the sheet 3 may be self-supporting between these points.

95 The sheet 3 passes out from the end of the leer onto a cutting table 23 where it is 100 severed into the desired sizes or sections as is now common in this art. The sheet 11 passes beneath the cutting table 23 and over a series of supporting rolls 24 onto 105 a cutting table 25 located slightly beyond 110 the cutting table 23 and with its cutting surface in a lower plane. In this way the two sheets may be conveniently handled individually after the annealing process is completed.

115 In Fig. 2 is shown a slight modification of the above in which the upper sheet 3 is not deflected upwardly but is carried through the leer in the same horizontally 120 plane in which it emerges from the draw 125

130

mechanism 8. The springing or deflecting process is applied entirely to the lower sheet 11, which is allowed to sink under its own weight along the series of rollers 19 and thence on to the conveying rollers 20. The rollers 19 throughout that portion of the conveyor where the sheet is being bent or deflected are preferably adjustable vertically so that they may be positioned along the curve that the sheet of glass will naturally take when bending under its own weight. As shown toward the left hand end of Fig. 2 some of the rollers are out of contact with the sheet, as it may be preferable to allow the sheet to bend freely at this point. The advantage of this second form of the apparatus lies in the fact that the upper sheet 3, which is normally the better of the two, is not subjected to any bending or springing operation and hence is less liable to breakage.

In a glass drawing mechanism of this type the sheets travel out of contact with one another throughout the major portion of the leer and thus both surfaces of the sheets are freely exposed to the tempering influence of the air within the leer and the annealing process will be more uniform than if the sheets pass through the leer in contact with one another. Also since the sheets emerge from the leer in separated planes, they may be each passed onto an individual cutting table, thus avoiding the inconvenience and possible loss through breakage and damage of sheets when it is attempted to cut two or more superimposed sheets upon the same cutting table.

Claims:

1. The process of producing sheet glass, comprising drawing a sheet of glass from a supply of molten glass, interposing a traveling surface of glass between the sheet and its supports during the flattening process, and then separating the sheet from its glass support and annealing the sheet.

2. The process of drawing sheet glass, comprising drawing a sheet of glass upwardly from a supply of molten glass, interposing a traveling surface of glass between the sheet and its supports while it is being bent into the horizontal and flattened, and then advancing the sheet out of contact with such glass support, through a leer.

3. The process of producing sheet glass, comprising the simultaneous drawing of a plurality of sheets from a supply of molten glass, passing the sheets in separable contact with one another about a bending roll and through a drawing and flattening apparatus, then separating the sheets and passing them out of contact with one another through a leer.

4. The process of producing sheet glass, comprising the simultaneous drawing of a

plurality of sheets from a supply of molten glass, passing the sheets in separable contact with one another about a bending roll and through a drawing and flattening apparatus, then separating the sheets and passing them out of contact with one another through a leer, and onto separate cutting tables.

5. The process of drawing sheet glass, comprising the simultaneous drawing of a plurality of separate sheets from a supply of molten glass, passing the sheets in separable contact with one another through the same drawing and flattening apparatus, then separating the sheets and annealing them out of contact with one another in the same leer.

6. The process of drawing sheet glass, comprising the simultaneous drawing of a plurality of separate sheets from a supply of molten glass, passing the sheets in separable contact with one another through the same drawing and flattening apparatus, then separating the sheets and annealing them out of contact with one another in the same leer, and delivering them to separate cutting tables.

7. The process of producing sheet glass, comprising the simultaneous drawing of a plurality of sheets from a supply of molten glass, drawing the sheets in separable contact with one another about a bending device, separating the drawn sheets and annealing them out of contact with one another in the same leer.

8. The process of producing sheet glass, comprising the simultaneous drawing of a plurality of sheets from a supply of molten glass, drawing the sheets in separable contact with one another about a bending device, separating the drawn sheets and annealing them out of contact with one another in the same leer, and delivering the sheets to individual cutting tables.

9. An apparatus for the manufacture of sheet glass, comprising a supply of molten glass, means for drawing therefrom a plurality of separate sheets of glass, a common bending device about which the sheets are passed in separable contact with each other, drawing means for the glass sheets, a leer, and separate conveyors for the sheets within the leer, comprising means for separating the sheets and advancing them through the leer out of contact with one another.

10. An apparatus for the manufacture of sheet glass, comprising a supply of molten glass, means for drawing therefrom a plurality of separate sheets of glass, a common bending device about which the sheets are passed in separable contact with each other, a common drawing and flattening means through which the sheets pass in separable contact with each other, a leer, and separate conveyors for the sheets within the leer,

comprising means for separating the sheets and advancing them through the leer out of contact with one another.

11. In an apparatus for drawing a plurality of separate continuous sheets of glass in separable contact with one another, a leer into which the sheets are advanced, and means within the leer for separating the sheets and advancing them individually through the leer.

12. In an apparatus for drawing a plurality of separate continuous sheets of glass in separable contact with one another, a leer into which the sheets are advanced, means within the leer for separating the sheets and advancing them individually through the leer, and a series of cutting tables beyond the leer, one sheet being advanced onto each table.

13. In an apparatus for drawing a plurality of continuous sheets of glass in separable contact with one another, a leer into which the sheets are advanced, supporting rollers for the lower sheet at one end of the leer, means for separating the sheets, and parallel series of rollers for advancing the separated sheets individually through the leer.

14. In an apparatus for drawing two continuous sheets of glass in separable contact with each other, a leer into which the sheets are advanced, rolls at the leer entrance for supporting the pair of sheets, a continuous series of advancing and supporting rolls for carrying the upper sheet horizontally through the leer, the first rolls of the series being of smaller diameter so that the lower sheet may be deflected therebeneath, and a series of advancing and supporting rolls for independently carrying the lower sheet through the leer.

15. In an apparatus for drawing sheet glass, a supply of molten glass, a bending roll, means for drawing two sheets of glass upwardly from the supply and over the roll in separable contact with one another, a leer into which the sheets are advanced, and means within the leer to separate the two sheets, and carry them independently through the leer.

16. In an apparatus for drawing sheet glass, a supply of molten glass, a bending roll, means for drawing two sheets of glass upwardly from the supply and over the roll in separable contact with one another, a leer into which the sheets are advanced,

means within the leer to separate the two sheets, and carry them independently through the leer, and separate cutting tables onto which the sheets are advanced from 60 the leer.

17. In an apparatus for drawing sheet glass, a supply of molten glass, a bending roll, means for drawing two sheets of glass upwardly from the supply and over the roll 65 in separable contact with one another, a leer into which the sheets are advanced, means within the leer to deflect the lower sheet downwardly from the upper sheet, and separate conveyors for advancing the separated sheets through the leer.

18. In an apparatus for drawing sheet glass, a supply of molten glass, a bending roll, means for drawing two sheets of glass upwardly from the supply and over the roll 70 in separable contact with one another, a leer into which the sheets are advanced, means within the leer to deflect the lower sheet downwardly from the upper sheet, separate conveyors for advancing the separated 75 sheets through the leer, and separate cutting tables onto which the sheets are advanced from the leer.

19. In an apparatus for drawing two sheets of glass in separable contact with one another, a leer into which the sheets are advanced, an upper series of supporting rollers in the leer onto which the upper sheet is advanced, a lower series of supporting rollers onto which the lower sheet is advanced, after being deflected downwardly, and means slidably supporting the edge portions of the upper sheet between the line of separation of the sheets and the first upper supporting roller.

20. In an apparatus for drawing two sheets of glass in separable contact with one another, a leer into which the sheets are advanced, an upper series of supporting rollers in the leer onto which the upper sheet is 100 advanced, a lower series of supporting rollers onto which the lower sheet is advanced after being deflected downwardly, and stationary supports projecting under the edge portions only of the upper sheet between the 105 line of separation of the sheets and the supporting rollers.

Signed at Toledo, in the county of Lucas and State of Ohio, this 29th day of Sept., 1921.

ARTHUR E. FOWLE.
